W. M. DUNCAN

CHAIN GRATE

Filed May 16, 1925

UNITED STATES PATENT OFFICE.

WILLIAM M. DUNCAN, OF ALTON, ILLINOIS.

CHAIN GRATE.

Application filed May 16, 1925. Serial No. 30,667.

This invention relates to improvements in chain grates and more particularly to the links adapted to form a chain grate. One of the objects of the invention is to produce 5 a simple and inexpensive chain grate where- in the draft serves as an effective cooling me- dium for the fuel-supporting portion of the grate, thereby preventing destructive over- heating of the simple grate links. Another 10 object is to improve the combustion by transmitting the draft to a relatively large portion of the fuel which contacts with the grate, and to more effectively distribute the draft through the fuel bed.

15 With the foregoing and other objects in view, the invention comprises the novel construction, combination and arrangement of parts hereinafter more specifically described and illustrated in the accompanying draw- 20 ings, wherein is shown the preferred embodiment of the invention. However, it is to be understood that the invention comprehends changes, variations and modifications which 25 come within the scope of the claims hereunto appended.

In the preferred form of the invention, each grate link is a simple casting enlarged 30 at the top to provide a fuel-supporting rib, and having pivot-receiving bosses below 35 said rib, the bosses being large enough to serve as spacers whereby the adjacent side faces of the fuel-supporting ribs are separated from each other to form draft inlet 40 passages between them. The fuel-support- 45 ing ribs have inclined fuel-receiving sur- faces extending upwardly from these pas- sages, so that the draft will contact with the fuel at the inclined surfaces. The draft is thus supplied directly to the lowermost par- 50 ticles of fuel which contact with the surface 55 of the grate, and this results in more perfect combustion of these fuel particles. The cooling action of the draft on the inclined fuel-supporting surfaces tends to prevent de- 60 structive overheating of the grate. Another 65 interesting condition lies in the fact that a fuel bed having a flat top surface will be deepest at the inclined faces where the draft is admitted, and this is desirable because it 70 results in a more uniform distribution of the draft.

Fig. I is a longitudinal section illustrating 75 a portion of a furnace provided with a chain grate embodying the features of this in- vention.

Fig. II is an enlarged perspective view of one of the grate links.

Fig. III is an enlarged section showing a pivot rod extending through several of the links.

The chain grate herein shown comprises 60 grate links A connected together by means of pivot rods 1 to form an endless chain structure. A power shaft 2 at the front of the furnace is provided with a suitable num- 65 ber of sprocket wheels 3 whereby the chain grate is driven, and a similar wheel, or roll, 4 is located at the rear of the grate. The draft is admitted through ports 5 to a com- 70 partment within the endless chain structure, 75 said compartment having a front wall 6, a rear wall 7, and a bottom wall 8 loosely sup- 80 ported on the lower portion of the grate and provided with an upturned rear margin which engages a stationary tube 9 to prevent 85 longitudinal displacement of said bottom wall 8. This wall 8 has openings 10 through which fine ashes and the like are discharged into the lower portion of the traveling grate.

A Z-bar 11 extending around the lower 80 margin of the draft compartment is adapt- 85 ed to receive loose sealing bars 12 which rest upon the bottom wall 8. As shown at 13, ashes will cooperate with the members 11 and 12 to form seals at the lower corners 85 of the draft compartment, and similar piles of ashes will be formed at the edges of the discharge openings 10.

Fuel is supplied through a hopper 14 90 above the front portion of the traveling grate, and the ashes are discharged at the rear where the grate moves downwardly at the roll 4. The fine ashes dropping from the fuel supporting portion of the grate will 95 fall through the draft compartment and pass out through openings 10 to the lower por- 100 tion of the traveling grate. The ashes in this portion of the grate are discharged where the links move upwardly in passing around the sprocket wheels 3. The lower 105 portion of the grate slides over the top of a stationary supporting member 15.

Channel bars 16 serve as partitions to 110 form several draft passages immediately be- 105 low the upper course of the grate, and the draft may be regulated by means of dampers 17 pivoted at 18, said dampers being move- 110 able toward and away from stationary wings 19. The rear damper 17' is movable toward and away from the rear wall 7.

Attention is now directed to the simple grate links A which carry the fuel from the hopper 14. Each link comprises a vertical web 20 with hollow bosses 21 to receive two of the pivot rods 1. A fuel-supporting rib 22 extends from the upper margin of the web 20, and this rib is provided with a narrow, elongated and substantially horizontal top face 23, substantially vertical side faces 24 and inclined fuel-supporting faces 25 extending downwardly from said top face to said side faces. The bosses 21 are wide enough to form separating members whereby the vertical side faces 24 of adjacent links are spaced apart to provide draft passages between them.

The elongated grate links are arranged lengthwise of the grate, and the draft passages between the faces 24 are formed longitudinally of the grate. The draft is forced upwardly through these passages and effectively distributed through the fuel bed. This draft is transmitted directly to the fuel particles contacting with the inclined faces 25, and the draft pressure is greatest at the deepest portions of the fuel bed which lie immediately above the draft inlets.

In this construction, the draft is an effective cooling medium for the fuel-supporting portion of the grate, and the several advantages can be obtained by using simple and inexpensive grate links. Each of the links herein shown is preferably a single casting wherein the vertical web 20, bosses 21 and fuel-supporting ribs 22 are formed integral with each other.

I claim:

A chain grate comprising grate links pivotally connected together and having solid ribs at their upper margins, the side faces of adjacent ribs being separated to form draft passages, the top of each of said solid ribs being provided with a narrow, elongated and substantially horizontal fuel-supporting surface extending longitudinally of the grate, and each of said solid ribs being provided with inclined fuel-supporting surfaces extending downwardly from opposite sides of said narrow fuel-supporting surface to the side faces of the rib.

In testimony that I claim the foregoing I hereunto affix my signature.

WILLIAM M. DUNCAN.
